UNITED STATES PATENT OFFICE.

JOHN THOMAS MCGRATH, OF FORT GRATIOT, MICHIGAN.

PNEUMATIC FLUE-CUTTER.

SPECIFICATION forming part of Letters Patent No. 747,565, dated December 22, 1903.

Application filed September 5, 1902. Serial No. 122,235. (No model.)

To all whom it may concern:

Be it known that I, JOHN THOMAS MCGRATH, master mechanic, of the town of Fort Gratiot, in the county of St. Clair, in the State of Michigan, have invented certain new and useful Improvements in Pneumatic Flue-Cutters, of which the following is a specification.

My invention relates to improvements in flue-cutters; and the object of the invention is to provide a simple, cheap, positive, independent driving means for the flue-cutter and for throwing the cutting-wheel outwardly against the interior periphery of the flue and designed to be operated pneumatically and, further, to provide a means for cleaning the inner surface of the flue before the cutting operation takes place; and it consists, essentially, of the novel arrangement and construction of parts, as hereinafter more particularly explained.

Figure 1 is a perspective view of my flue-cutter, showing it for the most part in section. Fig. 2 is a detail of the operating-piston and rod. Fig. 3 is a cross-section on line xx of Fig. 1. Fig. 4 is a similar view on line ab of Fig. 1. Fig. 5 is a detail of the scraper, showing its detachable connection to the end of the flue-cutter. Fig. 6 is a detail of the sleeve forming the connection between the hollow driving-shaft and the branch air-inlet pipe.

In the drawings like letters of reference indicate corresponding parts in each figure.

A is the casing of the flue-cutter, having a peripheral recess a .

B is a central rod provided with the segmental extension b .

C is a bar pivotally secured to the wall of the casing within the recess a . c is the cutting-wheel, journaled at the opposite end of the bar C.

b' represents spiral grooves formed in the central spindle B.

D is an air-cylinder secured to or forming part of the casing of the flue-cutter.

E is the hollow driving-shaft, operated by a suitable motor and designed to enter the head d of the cylinder D.

d' is a branch pipe connected to the hollow shaft by a sleeve d^2 and provided with a turn-cock d^3 . (See Fig. 1.)

In the hollow shaft E are formed openings e beneath the sleeve d^2 . The sleeve d^2 is held in place by the lock-nuts d^4 . This connection will enable the air to be fed into the driving-shaft E at any point in its rotation.

F is a piston designed to operate within the cylinder D and provided with a stem f , having an enlarged rectangular outer end f' .

f^2 is a recess into which the central rod B is designed to fit.

f^4 represents ball-bearings.

f^5 represents tap-screws having semicircular end recesses into which the spiral grooves b' the balls are designed to fit and have movement therein.

G is a compression-spring located between the piston F and the wall of the cylinder to carry the said piston back to its normal position when the cutter has finished operating on the flue.

H is a reduced portion of the cylinder made rectangular to form a guideway for the enlarged portion f' and prevent the rotation of the piston F.

H' is a cutting-knife or scraper attached to or forming part of the casing A and designed to clean the inner periphery of the flue before the cutting-wheel c is brought into operation, thereby preventing it becoming clogged or rendered inoperative.

Having described the principal parts involved in my invention, I shall briefly describe the operation of the same. The shaft is first caused to rotate by any suitable motor, and the device is moved forward, so as to bring the knife H' within the flue, and thereby in its rotation remove any accumulation of scale or rust or foreign matter from the interior of the flue previous to the cutter being brought into position. The device being brought still farther forward, the turn-cock d^3 then being opened air passes into the cylinder D, thus forcing the piston forward. By means of balls f^4 operating in the grooves b' a rotary movement is imparted to the spindle B. As the segmental end b of the spindle B rotates within the casing A it carries the wheel c outwardly into an operative position against the wall of the flue to cut it. When this operation is complete, the turn-cock d^3 is closed, thereby cutting off the air.

supply to the cylinder D. The spring G then operates to carry the piston F back to its normal position, and thereby a rotary movement is imparted in a reverse direction to the spindle B through the balls f⁴ and spiral ways b', allowing the cutting-wheel c to recede, and thus permit of the withdrawal of the tool.

It will be seen from this description that the cutting-wheel will be positively forced 10 against the interior of the flue, so as to act with the greatest efficiency on account of the bearings holding in their position in the spiral grooves, and thereby holding the segmental end of the spindle against the bar, so as 15 to keep a constant pressure on the bar, and consequently on the cutter when in use.

What I claim as my invention is—

1. In a flue-cutter, the combination with the casing having a radially-movable cutter, of a 20 spindle rotatably mounted in the casing, adapted when rotated to force said cutter outwardly, a reciprocating piston within the casing, and means whereby the reciprocation of the piston imparts rotary movement to said 25 spindle, substantially as described.

2. In a flue-cutter, the combination with the casing, the central spindle extending therethrough and the cutting-wheel adjusted and supported thereby, of a cylinder forming part 30 of the said casing and provided with an inlet-pipe, a piston designed to operate therein and suitable connections between the piston and the central spindle for imparting a turning movement to the spindle during its rotation 35 as and for the purpose specified.

3. In a flue-cutter, the combination with the rotatable casing, the central spindle extending therethrough and having spiral grooves formed therein and the cutting-wheel adjusted 40 and supported by the spindle, of a cylinder forming part of the said casing and provided with an inlet-pipe, a piston designed to operate therein, and provided with a central hollow stem into which the central spindle 45 is designed to extend, projecting portions formed in the interior of the stem and designed to enter the spiral groove to impart a turning movement to the spindle and means for returning the piston to its normal position 50 when not in operation as and for the purpose specified.

4. In a flue-cutter, the combination with the rotatable casing, the central spindle extending therethrough and having spiral grooves 55 formed therein and the cutting-wheel adjusted and supported by the spindle, of a cylinder forming part of the said casing and provided with an inlet-pipe, a piston designed to operate therein and provided with a central hollow stem into which the central spindle 60 is designed to extend, ball-bearings held within the spiral grooves by suitable cups and a resilient means for restoring the piston to normal location between the piston and the 65 end of the casing as and for the purpose specified.

5. In a flue-cutter of the class described, the

combination with the rotatable casing, the central spindle extending therethrough and having spiral grooves formed therein and a 70 cutting-wheel adjusted and supported by the spindle, of a cylinder attached to or forming part of the casing and having an air-inlet pipe and an outer rectangular recess, a piston located within the cylinder and provided with 75 a stem having a rectangular end having a central orifice designed to receive the spiral-grooved end of the spindle, balls located in the spiral grooves and set-screws designed to extend through the square portion of the stem and having cup-shape inner ends designed to receive and hold the balls in position as and for the purpose specified.

6. In a flue-cutter, the combination with the rotatable casing, the central spindle extending 80 therethrough and having spiral grooves formed therein and a cutting-wheel adjusted and supported by the spindle, of a cylinder attached to or forming part of the casing and having an air-inlet pipe and an outer rectangular 85 recess, a piston located within the cylinder and provided with a stem having a rectangular end having a central orifice designed to receive the spiral-grooved end of the spindle, balls located in the spiral grooves and 90 set-screws designed to extend through the square portion of the stem and having cup-shape inner ends designed to receive and hold the balls in position and a spring located between the piston and the end of the cylinder 95 100 as and for the purpose specified.

7. In a flue-cutter, the combination with the rotatable casing, the central spindle extending 105 therethrough and having spiral grooves formed therein, and a cutting-wheel adjusted and supported on the end of the spindle, of a cylinder, a piston located within the cylinder and operatively connected to the central spindle, and pneumatic means for operating the piston as and for the purpose specified. 110

8. In a flue-cutter, the combination with the rotatable casing, the central spindle extending 115 therethrough and having spiral grooves formed therein, and a cutting-wheel adjusted and supported on the end of the spindle, of a cylinder, a piston located within the cylinder and operatively connected to the central spindle, a hollow driving-shaft extending into the end of the cylinder and having 120 orifices intermediate of its length, a stationary sleeve through which such shaft extends and in which such shaft is designed to rotate, such sleeve being provided with an air-inlet pipe and being designed to cover the openings in the shaft as and for the purpose specified. 125

9. In a flue-cutter, the combination with the casing provided with an opening in its periphery and the central spindle extending through the center of the casing and having spiral grooves at the inner end, and a segmental outer end, and a bar pivotally connected to the casing in the opening of the casing 130 opposite the segmental end of the spindle, and the cutting-wheel journaled in the end

of the bar, of turning means extending into the spiral grooves and pneumatic means for operating such turning means as and for the purpose specified.

5 10. In a flue-cutter, the combination with the casing provided with an opening in its periphery and the central spindle extending through the center of the casing and having spiral grooves at the inner end, and a segmental outer end, and a bar pivotally connected to the casing in the opening of the casing opposite the segmental end of the spindle, and the cutting-wheel journaled in the end of the bar, of a piston provided with turning means extending into the groove and pneumatic means for operating the piston and means for restoring it to its normal position as and for the purpose specified.

15 11. In a flue-cutter, the combination with the spindle and a cutter adjusted and supported thereon, of a scraper secured at the

outer end of the spindle in advance of the cutter as and for the purpose specified.

12. In a device of the class described, a scraper adjustably held in advance end of the 25 cutter as and for the purpose specified.

13. In a device of the class described, the combination with the casing in advance of the cutter, of a scraper adjustably held upon the outer end of the casing as and for the purpose 30 specified.

14. In a device of the class described, the combination with the cutter having a threaded orifice in the end thereof, of a scraper having a working flattened outer end and a 35 threaded stem designed to fit into the threaded orifice in the end of the cutter as and for the purpose specified.
